GRINDING WHEEL DRESSING MECHANISM

Stanford P. Bruce, Detroit, Mich., assignor to
 Wheel Trueing Tool Company, Detroit, Mich.,
 a corporation of Delaware

Application February 5, 1949, Serial No. 74,775

4 Claims. (Cl. 125—11)

1

The present invention relates to a grinding wheel dressing assembly wherein dressing tools, particularly diamond tools, are used to true or dress the surface of an abrasive wheel.

As abrasive wheels become worn or otherwise out of true from prolonged use, it is customary practice to dress or true the cutting surface of the wheel by passing a cutting tool, such as a diamond point, across the surface thereof parallel to the axis of rotation of the wheel, to dress or reshape the wheel to its proper configuration. Continued use of a diamond dressing tool tends to wear the diamond point unevenly, resulting in worn surfaces, or "flats" being formed on the diamond, a condition which impairs its usefulness.

To overcome this objection, in my previously filed application Serial No. 744,749 entitled "Grinding Wheel Dressing Mechanism," filed April 29, 1947, now Patent No. 2,597,616, dated May 20, 1952, I have described a rotatable tool holder for mounting diamond dressing tools. This tool holder is capable of imparting intermittent step by step rotation to the diamond tool, so that all faces of the diamond tool are worn evenly, and the diamond ultimately acquires a generally pyramidal configuration of cutting surfaces. While this improvement has been eminently successful in prolonging the useful life of diamond tools, difficulties have arisen in mounting the tool in certain grinding wheel installations due to the limited amount of space available for mounting the dressing assembly and its adjuncts.

This invention relates to an improvement in grinding wheel dressing assemblies providing a mounting for indexing dressing tools from remote positions.

An object of the present invention is to provide a grinding wheel dressing assembly containing a rotatable tool holder which may be automatically rotated by means of a remote indexing mechanism.

Another object of the present invention is to provide a grinding wheel dressing assembly containing a rotatable tool holder which may be mounted on dressing machines where a limited amount of space is provided.

Other and further objects of the invention will become apparent from the following description and the discussion of the attached drawings.

In general, this invention provides a grinding wheel dressing assembly containing a rotatable dressing tool mounted in a conventional slide assembly for traversing movement across the surface of a grinding wheel, and remote actuating

2

means for imparting rotating movement to the dressing tool at the completion of the traversing movement across the surface of the grinding wheel.

5 A more complete description of the present invention will be made in connection with the attached drawings, in which:

Figure 1 is a fragmentary perspective view of the dressing assembly of the present invention mounted on a conventional Cincinnati centerless type grinding machine;

Figure 2 is a front elevational view of the gear box housing the rotatable diamond tool holder and the driving gear, with the cover removed;

Figure 3 is a cross-sectional view taken along line III—III of Figure 2, with parts in elevation;

Figure 4 is a longitudinal vertical sectional view of the remote indexing mechanism; and

Figure 5 is a cross-sectional view taken along the line V—V of Figure 4.

As shown on the drawings:

Reference numeral 10 denotes in general a grinder of the Cincinnati centerless type having an abrasive wheel 11 and a guard 12 spaced from and surrounding the periphery of the grinding wheel 11. Projecting through the guard 12 and slidably mounted therein is a conventional slide 13 containing a rotatable tool holder 14 and a diamond tool 15. The slide 13 is mounted for sliding movement in a direction parallel to the axis of the grinding wheel 11. A gear box 16 mounted on the slide 13 provides means for periodically rotating the tool holder 14 as will be hereinafter described.

35 The slide 13 is housed in a carriage 17 for sliding movement along a table 18 which has a stop 19 mounted at or near one end. The carriage 17 carries a ratchet wheel housing 20 containing a movable pin 21 projecting therefrom. A flexible cable 22 is also secured to the ratchet wheel housing 20 by means of a coupling 23. The other end of the flexible cable 22 passes through the guard 12 and terminates in the gear box 16. Attached to the stop 19 is a bracket 24 (Fig. 1) which serves to contact the slidable pin 21 projecting from the ratchet housing 20 when the slide assembly has reached its farthest limit of travel along the table 18. When the bracket 24 is contacted by the sliding pin 21, the pin 21 actuates a ratchet mechanism contained

40 in the ratchet housing 20 to rotate the same, the rotative movement of the ratchet being transmitted via the flexible cable 22 to the driving gear contained in gear box 16 which, in turn, 50 imparts a step-by-step rotation to the rotatable

tool holder 14 and the corresponding diamond point 15. The assembly is so arranged that the slidable pin 21 contacts the bracket 24 after the diamond tool 15 has completed its traverse across the face of the grinding wheel 11 and is out of contact with the grinding wheel 11. At such time the tool holder 14 is rotated to present a new cutting face to the surface of the grinding wheel 11.

The assembly shown in Figure 1 also includes pressure lines 25, a pressure gauge 26 and electric power lines 27.

The gear housing 16, as best shown in Figures 2 and 3, consists of a generally elliptical member 28 and a cover plate 29, the latter being secured to the member 28 by means of screws 30. The member 28 is provided with a cylindrical shaft 31 adapted to be mounted securely within the slide 13. Formed within the shaft 31 is an internal recess 32 which receives the pilot 33 of the tool holder 14.

The tool holder 14 is provided with an annular flange 34 and with a sprocket gear 35 having teeth 36. The tool holder 14 is also provided with an internal bore 37 for the reception of the diamond tool 15. The diamond tool 15 is secured within the tool holder 14 by a set screw threaded into an aperture 38 in the tool holder 14. A washer 39 is disposed about the flange portion 34 of the tool holder 14.

The sprocket gear 35 is meshed with a similar driving sprocket gear 40 having teeth 42, which is disposed against the inner surface of member 28 and spaced from the cover plate 29 by means of a spacer 41. This driving gear 40 contains a hub 60 rotatably mounted in a recess 46 of the cover plate 29. The driving gear 40 is actuated by attaching it to the inner flexible shaft 43 of the flexible cable 22, which includes a sheath 44 and a coupling 45. The coupling 45 is held in member 28 as by means of welded joints.

As best shown in Figures 4 and 5, the ratchet housing 20 consists of a base member 47 and a vertical housing 48 rigidly attached thereto.

The base 47 of the ratchet housing 20 is formed into a channel 49 for slidably containing a slide member 50. Secured to the slide 50 and movable therewith is the pin 21 which projects through an aperture 51 in a flange 52 projecting from the base 47. The slide 50 carries a pawl member 53 for actuating a ratchet wheel 54 secured to the inner shaft 43 of the flexible cable 22. A hub 61 of the ratchet wheel 54 is rotatably mounted within a recess 62 provided in the housing 48. The pawl 53 is pivotally mounted to the slide 50 by means of a pin 55, and is held in upright position by means of a spring 56 which urges the pawl 53 against an upstanding flange portion 57 of the slide 50. The slide 50 is also provided with a recess 58 to give added freedom of pivotal movement of the pawl 53 around the pin 55.

The slide 50 is normally held in a position such that the pawl 53 is out of contact with the ratchet wheel 54 by means of a spring 59 acting between the flange portion 52 and the slide 50.

The operation of the apparatus is as follows:

When the diamond tool 15 has made a traverse of the grinding wheel 11 and is out of contact therewith, the sliding pin 21 contacts the upstanding bracket 24, causing the pin 21 and the slide 50 to move in the channel 49 against the action of the spring 59. The pawl 53 thus contacts a tooth of the ratchet wheel 54 and rotates the ratchet wheel 54 through an angular dis-

tance represented by the spacing between successive teeth of the ratchet wheel 54. This rotational torque is transmitted by means of the inner shaft 43 of the flexible cable 22 to the driving gear 40 located in the gear housing 16. Movement of the driving gear 40 in turn rotates the sprocket gear 35 which is meshed therewith, causing the tool holder assembly 14 and the diamond tool 15 contained therein to rotate through a corresponding small arc.

As the carriage 17 is moved in the opposite direction for another pass across the surface of the abrasive wheel, the spring 59 urges the slide 50 back into its normal position. The pawl 53 slips under the lowermost tooth of the ratchet wheel 54 by virtue of its being pivoted at pin 55. This arrangement permits the pawl 53 to pass under the teeth of the ratchet wheel 54 without inadvertently rotating the ratchet wheel in the wrong direction. After the pawl 53 has passed out of contact with the teeth of the ratchet wheel 54, it is restored to its normal upstanding position against the flange portion 57 of the slide 50 by means of the action of the spring 56. The assembly is then in position for another traverse across the face of the grinding wheel.

From the foregoing it will be apparent that I have herein provided a grinding wheel dressing assembly utilizing a rotatable tool holder and have provided means for periodically rotating the tool holder from a remote position. It will be appreciated that the presently described apparatus is especially adapted for mounting in grinding wheel mechanisms wherein a limited amount of space is provided, or where the diamond tool is inaccessible for purposes of rotating the same after the traverse across the grinding wheel.

It will be apparent that many modifications may be made to the apparatus as herein described, and it is not my intention to limit the invention described herein other than as necessitated by the scope of the appended claims.

I claim as my invention:

1. A mechanism for automatically indexing a dressing tool at an end of its traverse over the face of a grinding wheel in an assembly including a bed, a carriage moveable over said bed, a tool holder mounted on said carriage and rotatable about its own axis, and a grinding wheel traversed by said carriage in its movement, said tool holder carrying a dressing tool which engages the periphery of said grinding wheel during said traverse, said mechanism comprising a first means coupled to said tool holder to rotate the same, a rotatable member mounted on said carriage remote from said first means, torque transmitting means connecting said rotatable member and said first means, a second means including a reciprocating pawl for rotating said rotatable member and a stop positioned on said bed beyond the end of the traverse of said carriage and arranged to be contacted by said reciprocating pawl and acting through said rotatable member, said torque transmitting means and said first means to rotate said tool holder.

2. A mechanism for automatically indexing a dressing tool at an end of its traverse over the face of a grinding wheel in an assembly including a bed, a carriage moveable over said bed, a tool holder mounted on said carriage and rotatable about its own axis, and a grinding wheel traversed by said carriage in its movement, said tool holder carrying a dressing tool which engages the periphery of said grinding wheel dur-

ing said traverse, said mechanism comprising a first means coupled to said tool holder to rotate the same, a rotatable member mounted on said carriage remote from said first means, a flexible cable means connecting said rotatable member and said first means, a second means including a reciprocating pawl for rotating said rotatable member and a stop positioned on said bed beyond the end of the traverse of said carriage and arranged to be contacted by said reciprocating pawl and acting through said rotatable member, said flexible cable means and said first means to rotate said tool holder.

3. A mechanism for automatically indexing a dressing tool at an end of its traverse over the face of a grinding wheel in an assembly including a bed, a carriage moveable over said bed, a tool holder mounted on said carriage and rotatable about its own axis, and a grinding wheel traversed by said carriage in its movement, said tool holder carrying a dressing tool which engages the periphery of said grinding wheel during said traverse, said mechanism comprising a first means coupled to said tool holder to rotate the same, a ratchet wheel mounted on said carriage remote from said first means, a flexible cable means connecting said ratchet wheel and said first means, a second means including a reciprocating pawl for rotating said ratchet wheel and a stop positioned on said bed beyond the end of the traverse of said carriage and arranged to be contacted by said reciprocating pawl and acting through said ratchet wheel, said flexible cable means and said first means to rotate said tool holder.

4. A mechanism for automatically indexing a dressing tool at an end of its traverse over the face of a grinding wheel in an assembly including a bed, a carriage moveable over said bed, a tool holder mounted on said carriage and rotatable about its own axis, and a grinding wheel

traversed by said carriage in its movement, said tool holder carrying a dressing tool which engages the periphery of said grinding wheel during said traverse, said mechanism comprising a gear train coupled to said tool holder to rotate the same, a ratchet wheel mounted on said carriage remote from said gear train, a flexible cable means connecting said ratchet wheel and said gear train, means including a reciprocating pawl for rotating said ratchet wheel and a stop positioned on said bed beyond the end of the traverse of said carriage and arranged to be contacted by said reciprocating pawl and acting through said ratchet wheel, said flexible cable means and said gear train to rotate said tool holder.
